US0D1106461S

(12) **United States Design Patent** (10) **Patent No.:** **US D1,106,461 S**
(45) **Date of Patent:** **** Dec. 16, 2025**

(54) **MOVEMENT ARM**

(71) Applicant: **DENTAL COMPONENTS LLC**,
Newberg, OR (US)

(72) Inventor: **Austin E. Unsworth**, Fort Mill, SC
(US)

(73) Assignee: **DENTAL COMPONENTS LLC**,
Newberg, OR (US)

(**) Term: **15 Years**

(21) Appl. No.: **29/928,644**

(22) Filed: **Feb. 14, 2024**

(51) LOC (15) Cl. **24-02**

(52) U.S. Cl.

USPC **D24/177; D14/447**

CLAIM

The ornamental design for a movement arm as shown and described.

DESCRIPTION

FIG. 1 is a perspective view of a movement arm showing the new design;

FIG. 2 is a front and left side elevation view thereof;

FIG. 3 is a rear and right side elevation view thereof;

FIG. 4 is a rear and left side elevation view thereof;

FIG. 5 is a front and right side elevation view thereof;

FIG. 6 is a top plan view thereof; and,

FIG. 7 is a bottom plan view thereof.

The broken lines of FIGS. 1-7 illustrate features of the movement arm that form no part of the claimed design.

1 Claim, 7 Drawing Sheets
